W. O. MELVIN.
DISPLAY ATTACHMENT FOR COUNTERS.
APPLICATION FILED JULY 1, 1921.

1,421,806.

Patented July 4, 1922.

UNITED STATES PATENT OFFICE.

WILLIAM O. MELVIN, OF LAKewood, OHIO.

DISPLAY ATTACHMENT FOR COUNTERS.

1,421,806.

Specification of Letters Patent. Patented July 4, 1922.

Application filed July 1, 1921. Serial No. 481,751.

To all whom it may concern:

Be it known that I, WILLIAM O. MELVIN, a citizen of the United States, and a resident of Lakewood, county of Cuyahoga, and State 5 of Ohio, have invented a new and useful Improvement in Display Attachments for Counters, of which the following is a specification, the principle of the invention being herein explained, and the best mode in which 10 I have contemplated applying that principle, so as to distinguish it from other inventions.

This invention relates to a display attachment for counters and like fixtures, and more 15 particularly comprises a casing, preferably of sheet metal, presenting at its upper side a series of openings through which articles of various character may be exhibited.

One of the objects of the invention is to 20 provide a simple means which may be applied to store counters and like fixtures in general use and serve to show the purchasing public samples of goods, the main supplies of which are kept in larger containers 25 elsewhere in the store. The attachment is well adapted to the display of staple groceries usually dealt with in bulk, such as beans, rice, coffee and similar articles. These specimens are placed in the special recep- 30 tacles provided and may be readily slipped into display position or withdrawn and changed, as desired.

While the device is best adapted for the particular use indicated, it is not intended 35 to limit its application thereto nor to imply that it cannot be utilized with other classes of goods than those mentioned, nor to restrict the place of attachment of the same to a counter. Also where the character of 40 the commodities permits the apparatus may be used to display goods which are intended to be sold directly from the containers.

In one form of my construction the device 45 may be applied to the flooring of a show window adjacent the glass front, and it obviously may also be positioned within a show case or in any suitable position upon a store fixture where it may be readily observed. To the accomplishment of the foregoing and 50 related ends, said invention, then, consists of the means hereinafter fully described and particularly pointed out in the claims.

The annexed drawing and the following 55 description set forth in detail certain structure embodying the invention such disclosed construction constituting, however, but one

of various structural forms in which the principle of the invention may be used.

In said annexed drawing:

Fig. 1 is a perspective view showing my 60 display attachment affixed to a counter;

Fig. 2 is a transverse vertical section taken along the line 2—2 shown in Fig. 1;

Fig. 3 is a transverse vertical section showing my device attached to a horizontal 65 support;

Fig. 4 is a perspective view of a preferred form of container for merchandise which I use in connection with my display attachment; 70

Fig. 5 is a horizontal section taken along the line 5—5 shown in Fig. 4; and

Fig. 6 is a rear elevation of my attachment showing the means for holding the individual containers behind the display 75 openings of the casing.

As is shown in Figs. 1, 2 and 3 of the drawing, the case or frame, 1, which is preferably constructed of thin sheet metal, has a series of openings, 2, of substantially rectangular outline and is provided at its upper edge with an inclined portion, 3, made integrally therewith and folded upon itself for strengthening purposes. This inclined portion of the attachment is designed to be held 80 securely against the under side of the projecting edge of the top board of a store counter by means of nails, screws or other fastening elements. In the rear of each of the openings a resilient tongue, 4, is securely 85 attached to such inclined edge and extends downwardly parallel to and in spaced relation from the front face of the casing. The lower edge of the casing is provided with an up-turned flange, 5, similarly spaced from 90 the front face of the casing and extending continuously the full length thereof. The ends, 6, of the case are closed by metallic 95 portions having an inwardly turned flange, 7, to make the structure more rigid. These 100 flanges are substantially continuous with the up-turned flange at the bottom of the casing. The end walls of the casing may be of greater width at their point of connection with the bottom flange than at their upper 105 portions and the inclined upper edge of the casing may likewise be of lesser width than that of the lower edge of the casing. The lower corners, 8, of the frame are preferably rounded, as shown, in Fig. 1.

Supporting strips, 9, attached to the lower edge of the casing may be provided, as

clearly shown in Figs. 2 and 3. When the display attachment is applied to the under edge, 11, of a store counter, 12, the supporting strips are bent downwardly at their inner ends, 13, and nails or other fastening devices, 14, are applied to the store fixture through such downwardly turned portions. When the attachment is to be used in a show window or above a store fixture, the supporting strips are not bent at an angle at their lower ends and constitute the sole support for the display fixture and may have a series of fastening elements such as screws or nails, 15, fastened therethrough at suitable intervals as clearly illustrated in Fig. 3. The individual containers, 21, used with the case or frame just described are illustrated in Figs. 4 and 5. They are preferably formed of a single piece of sheet metal, the sides, 22, being turned upwardly to form a box-like receptacle of the desired depth. Three of the said sides are then formed so as to provide grooves, 23, of appropriate size to receive a sheet of glass, 24, which may be used as the top or cover for the container. The edge, 25, of the remaining up-turned side, instead of being formed into a groove, is turned backwardly so as to provide a reinforcing edge for the container at that point and permit the free insertion of the glass within the grooved portions formed on the upper edges of the adjacent sides.

From the foregoing description, the manner of using my display device will be obvious. The goods which it is desired to display are placed in the individual containers and the glass cover plate is slipped into position thereover. The containers are then inserted beneath the resilient tongues of the casing or frame and forced upwardly to the full extent of the space allowed, and then lowered into engagement with the flanges upon the lower rear side of the casing. This securely holds them in position and their ready removal is accomplished by reversing the operation just described.

This construction is one of great simplicity and is very economical to manufacture. It provides a means of utilizing most advantageously space which ordinarily is not used for the display of goods and the preferred position beneath the front edge of a counter is such as to invite the attention of a customer who is making purchases.

Other modes of applying the principle of my invention may be employed instead of the one explained, change being made as regards the construction herein disclosed, provided the means stated by any of the following claims or the equivalent of such stated means be employed.

I therefore particularly point out and distinctly claim as my invention:—

1. A display attachment for store fixtures comprising a casing provided with a series

of display openings and having an inclined portion through which fastening means may be placed and a series of inclined supporting strips at the lower edge of said casing, an up-turned flange adjacent the base of said casing, a series of resilient tongues attached to said inclined portion of the casing, and extending downwardly in the rear of each of said openings, and a series of containers adapted to be removably engaged behind said openings.

2. A display attachment for store fixtures comprising a casing provided with a series of display openings and having an inclined portion through which fastening means may be placed and series of inclined supporting strips at the lower edge of said casing, an up-turned flange adjacent the base of said casing, and extending downwardly in the rear of each of said openings, a series of box-like containers provided with transparent covers and adapted to be seated within said up-turned flange and engaged by said resilient tongues.

3. A supplementary attachment for store fixtures comprising a casing angularly supported from the under edge of the fixture and provided with a single series of display openings longitudinally arranged; a series of containers adapted to be seated behind said openings, and fastening elements for removably holding said containers in position.

4. A supplementary display attachment for store fixtures comprising a casing provided with a series of display openings longitudinally arranged; a series of containers adapted to be seated behind said openings and a fastening element for removably holding each of said containers in position, said fastening element comprising a flange portion on said casing and a resilient tongue in spaced relation to the front face of said casing.

5. A display attachment for store fixtures comprising a casing angularly supported from the under edge of a fixture and provided with a single series of display openings longitudinally arranged, a series of containers adapted to be seated behind said openings, fastening elements for removably holding said containers in position and an integral supporting member in angular relation to the casing for securing the same to said store fixture.

6. A display attachment for store fixtures comprising a casing provided with a series of display openings longitudinally arranged, a series of containers adapted to be seated behind said openings, fastening elements for removably holding said containers in position, an integral supporting member in angular relation to the casing for securing the same to said store fixtures, and a series of supporting strips attached to the lower edge of said casing and positioned in angular re-

lation thereto, for holding said display attachment upon said store fixtures.

7. A supplementary display fixture for a store counter formed of a body of light sheet material, means for positioning said body in angular relation to the front edge of said counter, and a plurality of display members supported on said fixture, adapted to be presented at an angular relation to the top surface of said counter for convenient observation from a position in front of said counter.

8. In an article of the class described the combination of a supplementary display fix-

ture for a store counter formed of sheet material, fastening means angularly related to 15 said fixture for connecting the same beneath the projecting edge of a store counter, a plurality of removable display elements supported on said attachment, and means co-acting with said elements for forming a substantially smooth unbroken surface upon the 20 upwardly inclined face of the assembled attachment.

Signed by me this 28 day of June, 1921.

WILLIAM O. MELVIN.
